UNITED STATES PATENT OFFICE.

CHARLES STEIN, OF PARIS, FRANCE, ASSIGNOR TO SOCIETE CH. M. STEIN & CIE., OF PARIS, FRANCE, A CORPORATION OF FRANCE.

REGENERATIVE FURNACE.

1,350,624.

Specification of Letters Patent. Patented Aug. 24, 1920.

Application filed April 30, 1919. Serial No. 293,820.

To all whom it may concern:

Be it known that I, CHARLES STEIN, citizen of the French Republic, residing at Paris, Department of the Seine, in France, and whose post-office address is 31 Boulevard Pèreire, in the said city, have invented certain new and useful Improvements in or Relating to Regenerative Furnaces; and I do hereby declare the following to be a full, clear, and exact description of the invention, such as will enable others skilled in the art to which it appertains to make and use the same.

The present invention has for its object a vertical continuously regenerative furnace intended more particularly for the reheating of ingots to the temperature necessary for forging or rolling.

The invention is described hereinafter in detail with reference to the accompanying drawings which represent, by way of example and diagrammatically, a constructional form of the furnace.

Figure 1 represents the furnace in vertical section on the line C, D, E, F of Fig. 2.

Fig. 2 represents the furnace in plan on the section A B of Fig. 1.

Fig. 3 represents a vertical section of Fig. 2 on the line G, H, I, J.

Fig. 4 shows a detail illustrating the construction of the recuperator.

In the drawing, 1 is a gallery by which the gases of combustion arrive and which may be common to a series of furnaces of the same type, 2 is a damper for regulating the flow of the gases by the passages 3 and 4 into the working chamber or hearth 5, 6 is a flue by which the air to support combustion arrives which passes through the passage 7, the recuperator 8, and the passages 9, 10 and 11 to be mixed in 4 with the gases and cause the combustion thereof. The products of this combustion are evacuated through the flues 12 through the recuperator 8 and the flues 13, 14 and 15 and pass into the smoke collector 17. The recuperator is of hollow tile like construction, arranged in spaced vertical tiers, allowing for the transverse passage of the products of combustion and by reason of the hollow formation of the units comprising the tiers, vertical openings are provided for the passage of air, as clearly shown in Fig. 4. The regulation of the draft is produced by a damper

located at 16. The hearth communicates by 65 the passage 18 with the cleaning pit 19.

The action of the furnace is as follows:

The gas arrives by the gallery 1, passes through 2 and 3 up to the entrance to the hearth at 4, and at the same time, the air to 60 support combustion enters by the passages 6 and 7, passes through the recuperator 8 where it is heated, then passes through the passages 9, 10 and 11 to arrive at 4 where it meets the gas and mixes with this latter to 65 produce suitable combustion and heat the ingots which are placed in the hearth 5. The products of the combustion pass by the passages 12, 13 and 14, heat the air which circulates in the opposite direction in the recuperator and pass into the passage 15 whence they are evacuated into the smoke collector 17. The supplies of gas and air and also the exit of the smoke can be regulated by means of special dampers. 75

This continuous regenerative furnace possesses over the inversion type of furnace generally adopted, the advantage that it is of more simple construction and consequently more economical.

In these arrangements the cleaning pit is completely separated, the recuperator is situated completely outside the hearth the supplies of gas, and secondary air and the exit of the smoke are on the other side of the 80 cleaning pit, and can be regulated, each by a special damper.

The arrangement of this furnace permits of its being constructed in batteries of indefinite number, and each furnace can be 90 regulated or extinguished individually.

I claim:

1. A vertical furnace of the class described, comprising a hearth, means for admitting and burning therein a combustible mixture of air and gas, means for exhausting the products of combustion therefrom, a recuperator through which the incoming air passes and through which the outgoing products of combustion pass for heating said 95 air, and a smoke collector for the final exhausting of the products of combustion provided with means for regulating said exhaust. 100

2. A vertical furnace of the class described, consisting of a number of complete, separate and independent units having in common, a cleaning pit, a gas supply 105

gallery and smoke collector, each of said units comprising a hearth, means for admitting therein a combustible mixture of gas and heated air, means for exhausting the 5 products of combustion therefrom, a regenerator through which the incoming air passes and through which the outgoing products of combustion pass for heating said air, and means for cutting out one or more 10 of the separate units without interfering with the continuous operation of the remaining units and the furnace as a whole.

3. A vertical furnace of the class described, consisting of a number of complete, 15 separate and independent units having in common a gas supply and smoke collector, each of said units being provided with a hearth, passage-ways connecting said gas supply with a mixing chamber adjacent the

hearth, an air passage-way communicating 20 with said mixing chamber, a regenerator through which the air passes before entering said air passage-way, another passage-way leading from the hearth to the regenerator for conducting the products of combustion therethrough, said regenerator so constructed and positioned that the air will pass upwardly and the products of combustion downwardly, and regulating means for the admission of the gas to the mixing chamber and also for the admission of the air to 25 the generator and the exhausting of the products of combustion from said generator, the whole forming a furnace of continuous 30 operation.

In testimony whereof I affix my signature.

CHARLES STEIN.
